ABSTRACT

A sexual stimulation device includes: a main body; an elongated arm configured to be placed in a vagina, the elongate arm connected to the main body and including a first stimulation portion arranged at a distal end of the elongated arm away from the main body, the first stimulating portion configured for stimulating a first region; a second stimulation portion configured for stimulating a second region, the second region being different from the first region; and a third stimulation portion configured for stimulating a third region. The third region is different from the first stimulating region and the second stimulating region, the second stimulation portion and the third stimulation portion are respectively arranged at opposite sides of the elongated arm, a length of the second stimulation portion and a length of the third stimulation portion are shorter than a length of the elongated arm.

RELATED APPLICATIONS

This application claims the benefit of priority to Chinese Patent Application Number 202420269198.2 filed on Feb. 2, 2024, Chinese Patent Application Number 202421779259.6 filed on Jul. 25, 2024, Chinese Patent Application Number 202421779272.1 filed on Jul. 25, 2024, Chinese Patent Application Number 202421779281.0 filed on Jul. 25, 2024, Chinese Patent Application Number 202421779288.2 filed on Jul. 25, 2024, in the China National Intellectual Property Administration. The entire contents of the above-identified application are hereby incorporated by reference.

TECHNICAL FIELD

The present disclosure relates to the technical field of sexual stimulation, in particular to a sexual stimulation device used for females.

BACKGROUND

With societal advancements, there's been a notable enhancement in living standards, leading to a heightened focus on the quality of sexual experiences. To cater to diverse sexual desires across different genders and anatomies, all kinds of sexual stimulation devices have been provided.

Currently, the majority of commercially available products are handheld stimulating devices. A handheld stimulating device may include a handle and a stimulating member coupled with the handle. These devices typically have special textures on outer surfaces, unique shapes, and/or vibration members to deliver effects. However, there are also many problems, such as only a single area is being stimulated, and/or only one mode of stimulation is available, which limits the ability of the devices to provide more comprehensive or enhanced pleasurable experiences.

BRIEF DESCRIPTION OF DRAWINGS

Implementations of the present disclosure will now be described, by way of embodiment, with reference to the attached figures.

FIG. 1 is a three-dimensional structural diagram of a first embodiment of a sexual stimulation device according to the present disclosure.

FIG. 2 is an exploded view of the sexual stimulation device shown in FIG. 1.

FIG. 3 is an exploded view of a partial structure of the sexual stimulation device shown in FIG. 2.

FIG. 4 is a sectional view of the sexual stimulation device shown in FIG. 1.

FIG. 5 is a schematic view illustrating the sexual stimulation device shown in FIG. 1, in a swinging state.

FIG. 6 illustrates a view of a second stimulation portion and a third stimulation portion of the sexual stimulation device shown in FIG. 1, the second and the third stimulation portions being attached to an inner wall of an object.

FIG. 7 is a schematic representation of a first state of the sexual stimulation device shown in FIG. 1.

FIG. 8 is a schematic representation of a second state of the sexual stimulation device shown in FIG. 1.

FIG. 9 is a three-dimensional structural diagram of a second embodiment of a sexual stimulation device according to the present disclosure.

FIG. 10 is a sectional view of the sexual stimulation device shown in FIG. 9.

FIG. 11 is a three-dimensional structural diagram of a third embodiment of a sexual stimulation device according to the present disclosure.

FIG. 12 is an exploded view of the sexual stimulation device shown in FIG. 11.

FIG. 13 is a sectional view of a partial structure of the sexual stimulation device shown in FIG. 12.

FIG. 14 is a sectional view of the sexual stimulation device shown in FIG. 11.

FIG. 15 is a three-dimensional structural diagram of a fourth embodiment of a sexual stimulation device according to the present disclosure.

FIG. 16 is an exploded view of the sexual stimulation device shown in FIG. 15.

FIG. 17 is an exploded view of a partial structure of the sexual stimulation device shown in FIG. 16.

FIG. 18 is a sectional view of the sexual stimulation device shown in FIG. 15.

FIG. 19 is a three-dimensional structural diagram of a fifth embodiment of a sexual stimulation device according to the present disclosure.

FIG. 20 is a three-dimensional structural diagram of a sixth embodiment of a sexual stimulation device according to the present disclosure.

FIG. 21 is a sectional view of the sexual stimulation device shown in FIG. 20.

FIG. 22 is a three-dimensional structural diagram of the sexual stimulation device shown in FIG. 20, with a cover member being removed.

FIG. 23 is an exploded view of a partial structure of the sexual stimulation device shown in FIG. 22.

FIG. 24 is a partial sectional view of the sexual stimulation device shown in FIG. 23.

FIG. 25 is a partial enlarged view of the sexual stimulation device shown in FIG. 23.

FIG. 26 is a three-dimensional structural diagram of a seventh embodiment of a sexual stimulation device with a cover member being removed according to the present disclosure.

FIG. 27 is an exploded view of a partial structure of the sexual stimulation device shown in FIG. 26.

FIG. 28 is a sectional view of the sexual stimulation device shown in FIG. 26.

DETAILED DESCRIPTION

Embodiments of the present disclosure will be described in detail hereinafter with reference to the accompanying drawings.

First Embodiment

Referring to FIG. 1 to FIG. 8 to illustrate the sexual stimulation device 100 of the present disclosure.

The present disclosure provides a sexual stimulation device 100, which is configured for being partly inserted into a vagina of a female for sexual stimulation. Specifically, the sexual stimulation device 100 includes a main body 10, an elongated arm 20 having a length direction which defines a longitudinal direction X of the sexual stimulation device 100, a pair of stimulation portions 30 and 40 symmetrical to each other, a driving mechanism 50, a first motor 60, a second motor 70, and a control circuit 101. The main body 10 may be shaped to be easily handheld by a user in use. The elongated arm 20 and the pair of stimulation portions 30 and

40 are directly coupled to a same end of the main body 10. Each of the elongated arm 20 and the stimulation portions 30 and 40 substantially extends along the longitudinal direction X of the sexual stimulation device 100. The driving mechanism 50 and the control circuit 101 are accommodated in the main body 10. The driving mechanism 50 is coupled to the elongated arm 20, the pair of stimulation portions 30 and 40, and the control circuit 101, therefore, under the control of the control circuit 101, the driving mechanism 50 is capable of driving the elongated arm 20 and the pair of stimulation portions 30 and 40 to do predefined motions. In this embodiment, the elongated arm 20 is driven to telescoping motions, and the stimulation portions 30 and 40 are driven to swing. In this embodiment, the elongated arm 20 and the pair of stimulation portions 30 and 40 are arranged along an arranged line which is parallel to a width direction of the elongated arm 20. The width direction of the elongated arm 20 also acts as a lateral direction Y of the sexual stimulation device 100. The pair of stimulation portions 30 and 40 includes a second stimulation portion 30 disposed at one side of the elongated arm 20 and a third stimulation portion 40 disposed at another side of the elongated arm 20 opposite to the one side of the elongated arm 20. The second stimulation portion 30, the elongated arm 20 and the third stimulation portion 40 at least partially overlap with one other in the lateral direction of the sexual stimulation device 100, while at least a part of the second stimulation portion 30, the elongated arm 20 and the third stimulation portion 40 are spaced from one another at a direction which is orthogonal to the arranged line.

In one embodiment, the elongated arm 10 is swingable in a first swing plane A perpendicular to the arranged line. The second stimulation portion 30 is configured to swing in a second swing plane B which is substantially parallel to the first swing plane A. The third stimulation portion 40 is configured to swing in a third swing plane C which is substantially parallel to the first swing plane A.

In one embodiment, the second stimulation portion 30 is capable of swinging in a second swing plane B which obliquely intersects with the first swing plane A. A first included angle α defined by the first swing plane A and the second swing plane B is in a range of 0-60 degrees. The third stimulation portion 40 is capable of swinging in a third swing plane C which obliquely intersects with the first swing plane A. A second included angle β defined by the first swing plane A and the third swing plane C is in a range of 0-60 degrees. A third included angle γ defined by the second swing plane B and the third swing plane C is in a range of 0-90 degrees.

The main body 10 includes a first accommodating portion 11 configured for accommodating the driving mechanism 50 and the control circuit 101. In the present embodiment, the main body 10 includes a first end 12 and a second end 13 arranged opposite to the first end 12. The first end 12 is a free end of the sexual stimulation device 100. The elongated arm 20, the second stimulation portion 30 and the third stimulation portion 40 are coupled to the first end 12 of the main body 10.

In this embodiment, the main body 10 is roughly elliptical in shape and has a handheld portion configured for being held by a hand of the female.

In addition, the main body 10 further includes a button (not shown), which is configured for controlling the control circuit 101 of the sexual stimulation device 100.

In the present embodiment, the elongated arm 20 is connected to the main body 10 and includes a connecting portion 21 extending from the first end 12 of the main body

10 and a first stimulation portion 22 extending from one end of the connecting portion 21 away from the main body 10. The first stimulation portion 22 is configured to stimulate a first region 201 of the female. When the elongated arm 20 is inserted into the vagina of the female, the elongated arm 20 can massage and stimulate the first region 201 of the vagina by the first stimulation portion 22, thereby obtaining a better sexual experience. Especially, compared to an opening of the vagina, the first region is much closer to a deepest side of the vagina.

In one embodiment, the length of the elongated arm 20 is in a range of 3 cm to 30 cm, which can be exemplified as 3 cm, 5 cm, 8 cm, 10 cm, 15 cm, 20 cm, 25 cm, 30 cm and the like, which is not limited herein.

15 In this embodiment, referring to FIG. 1 and FIG. 6, the connecting portion 21 comprises a neck portion 23 coupled to the main body 10, a width W1 of the neck portion 23 is much smaller than the width W2 of the first stimulation portion 22. The neck portion 23 comprising two concave portions 231 at on two opposite sides of the neck portion 23. The second stimulation portion 30 and the third stimulation portion 40 are disposed beside the two concave portions 231. In this embodiment, the second stimulation portion 30 and the third stimulation portion 40 are disposed at the two opposite sides of the neck portion 23 beside the concave portions 231. The sexual stimulation device 100 is switchable between an original state and a pressed state, in the pressed state, the second stimulation portion 30 and the third stimulation portion 40 are pressed towards the corresponding concave portions 231. In the original state, a maximum lateral width W3 from the second stimulation portion 30 to the third stimulation portion 40 is larger than the width W2 of the first stimulation portion 22. When the elongated arm 20 is being inserted into the vagina, the second stimulation portion 30 and the third stimulation portion 40 are pressed and at least partially accommodated in the corresponding concave portions 23, such that the second stimulation portion 30 and the third stimulation portion 40 are changed into the pressed state. In the pressed state, the maximum lateral width W3 from the second stimulation portion 30 to the third stimulation portion 40 is substantially equal to the width W2 of the first stimulation portion 22.

40 The elongated arm 20 further comprises a second accommodating portion 24 formed at the first stimulation portion 22 configured for accommodating the first motor 60. The first motor 60 drives the first stimulation portion 22 to move, such as vibration, rotation, extension, flowing, hollowing out and other different movements by control of the control circuit 101. When the elongated arm 20 is inserted into the vagina, the elongated arm 20 can further stimulate the first region 201 of the vagina of the female.

45 In the present embodiment, the first motor 60 is provided with a battery (not shown) configured to supply power to the first motor 60. The battery is also received in the second accommodating portion 24. Therefore, it is possible to effectively simplify the wiring inside the sexual stimulation device 100 and save space.

50 Referring to FIG. 5 to FIG. 8, each of the second stimulation portion 30 and the third stimulation portion 40 extend from the main body 10 along a direction parallel to or obliquely intersected with the longitudinal direction X of the sexual stimulation device 100. The second stimulation portion 30 and the third stimulation portion 40 are arranged at opposite sides of the elongated arm 20, a length of the second stimulation portion 30 and a length of the third stimulation portion 40 are much shorter than a length of the elongated arm 20, the second stimulation portion 30 is

configured for stimulating a second region **301** of the female, the second region **301** is different from the first region **201**, the third stimulation portion **40** is configured for stimulating a third region **401** of the female, the third region **301** is different from the first region **201** and the second region **301**. The elongated arm **20** is arranged between the second region **301** and the third region **401**.

In the present embodiment, a length of the elongated arm **20** is much greater than at least one of a length of the second stimulation portion **30** and a length of the third stimulation portion **40**. For example, the length of the elongated arm **20** is more than twice of each of the lengths of the second stimulation portion **30** and the third stimulation portion **40**. In the present embodiment, the lengths of the second stimulation portion **30** and the third stimulation portion **40** are in a range of $\frac{1}{4}$ to $\frac{1}{2}$ of the length of the elongated arm **20**.

An end of the elongated arm **20** that is most further away from the main body **10** relative to at least one end of the second and third stimulation portions **30,40** is insertable into a deep position inside the vagina, the at least one end of the second and third stimulation portions **30,40** is deposited at an area adjacent to an opening of the vagina. That is, the second region **301** and the third region **401** (shown in FIG. 7) are adjacent to the opening of the vagina, while the first region **201** is adjacent to the deepest area of the vagina. In a use circumstance, the elongated arm **20** inserts into the vagina to stimulate, the second stimulation portion **30** and the third stimulation portion **40** are also insert into the vagina together with the elongated arm **20**. In this use circumstance, the second region **301** and the third region **401** are in the vagina of the female (shown in FIG. 7). In another using circumstance, the elongated arm **20** inserts into the body, the second stimulation portion **30** and the third stimulation portion **40** abut the periphery of the vagina. In this use circumstance, the second region **301** and the third region **401** are located at outside of the vagina (as shown in FIG. 8). Users can thus obtain a better massage stimulation effect.

In addition, the second stimulation portion **30** and the third stimulation portion **40** are configured to swing. The control circuit **10** is configured to cause the sexual stimulation device **100** to be in a first control mode or in a second control mode. In the first control mode, the second stimulation portion **30** and the third stimulation portion **40** swing at a same frequency in a same swing direction for a preset time period, in the second control mode, the second stimulation portion **30** and the third stimulation portion **40** swing at a same frequency in opposite swing directions for a preset time period.

In some embodiments, the second stimulation portion **30** and the third stimulation portion **40** are configured to swing reciprocally relative to the elongated arm **20** such that the second and the third stimulation portions **30,40** move closer to or further from the elongated arm **20**. The second stimulation portion **30** and the third stimulation portion **40** can predefined to swing in a same direction at a certain time, such as, both of them swinging towards left, or predefined to swing in opposite directions at a certain time, such as, the second stimulation portion **30** swinging towards left while the third stimulation portion **40** swinging towards right.

In this embodiment, the second stimulation portion **30** and the third stimulation portion **40** are swingable along a thickness direction **Z**. Specifically, the second stimulation portion **30** and the third stimulation portion **40** are predefined to swing synchronously. The second stimulation portion **30** and the third stimulation portion **40** swing towards a same direction or opposite directions at a certain time.

In other embodiments, each of the second stimulation portion **30** and the third stimulation portion **40** includes a connecting end **301, 401** connecting with the main body **10** and a distal end **302, 402** away from the main body **10**. The distal end **302, 402** is rotatable around a central axis thereof.

In addition, at least one of the distal ends **302, 402** of the second stimulation portion **30** and the third stimulation portion **40** is provided with the second motor **70**. The second motor **70** is configured to drive the corresponding distal end **302, 402** to vibrate. In this way, the second/third stimulation portion **30/40** having the second motor **70** vibrate while swinging, thereby providing the user with a better experience.

In this embodiment, each of the second stimulation portion **30** and the third stimulation portion **40** is provided with the second motor **70**. In the present embodiment, the second motor **70** is a vibration motor capable of generating vibrations in a high frequency.

In the present embodiment, the second motor **70** has a battery (not shown) in the distal end for supplying power to the second motor **70**. Thereby effectively simplifying the wirings inside the sexual stimulation device **100**.

In this embodiment, each of the second stimulation portion **30** and the third stimulation portion **40** has a roughly columnar structure.

Referring to FIG. 2 to FIG. 4, the driving mechanism **50** includes a driving motor **51**, a transmission **52** and two driver portions **53** arranged in the first accommodating portion **11**. The driving motor **51** is connected to the transmission **52** configured for changing rotation speeds of the driving motor **51**, thereby controlling the frequency of the elongated arm **20**, the second stimulation portion **30** and the third stimulation portion **40**. The two driver portions **53** are configured to drive the corresponding stimulation portion to move by the drive of the driving motor **51**, one end of each of the two driver portions **53** engages with the transmission **52**, and another end of each of the two driver portions **53** is inserted into corresponding one of the second stimulation portion **30** and third stimulation portion **40**, so as to drive the second stimulation portion **30** and the third stimulation portion **40** to move by the drive of the driving motor **51**.

In this way, by driving the second stimulation portion **30** and the third stimulation portion **40** to swing under the effect of one driving motor **51**, thereby satisfying driving mechanisms **50**.

The sexual stimulation device **100** further includes a cover member **90** having a hardness less than the two driver portions **53**. In this embodiment, a portion of the cover member **90** corresponding to the elongated arm **20**, the second stimulation portion **30** and/or the third stimulation portion **40** is seamless so as to provide one continuous skin-like surface that is smooth and soft.

In this embodiment, each of the second two stimulation portion **30** and the third stimulation portion **40** comprises the cover member **90** having a hardness less than a portion of the driving mechanism **50** which is connected to the second stimulation portion **30** and the third stimulation portion **40**.

In the present embodiment, the second end **12** of the main body **10** is exposed from the cover member **90**. In another words, an outer surface of the second end **12** of the main body **10** is not wrapped by the cover member **90**. In other embodiments, the cover member **90** can also wrap the entire surface of the main body **10**, which is not limited herein.

A recess **15** is formed in an outer surface of the main body **10** at a location adjacent to the second end **12**. A protruding portion **92** is formed at an end of the cover member **90**. The

protruding portion **92** is received into the recess **15** to further prevent the cover member **90** from detaching from the main body **10**.

In addition, the sexual stimulation device **100** further includes a shell **80** having a hardness larger than that of the cover member **90**. At least one of the first accommodating portion **11** and the second accommodating portion **24** are defined by the shell **80**. The cover member **90** covers the shell **80** at the second stimulation portion **30** and the third stimulation portion **40**.

Second Embodiment

The second embodiment of the present disclosure will be illustrated below based on FIG. 9 and FIG. 10. In addition, for the convenience of illustration, the same reference numerals are marked for components with the same function as those described in the above embodiments, and their illustrations are omitted.

In the present embodiment, a connecting portion **21A** of the elongated arm **20A** of the sexual stimulation device **100B** is roughly cylindrical. The size of the connecting portion **21A** is slightly less than that of a first stimulation portion **22A**. A neck portion **23A** is formed between the connecting portion **21A** and the first stimulation portion **22A**.

A top end of the elongated arm **20A** is higher than each one of a top end of the second stimulation portion **30A** and the third stimulation portion **40A**. The second stimulation portion **30A** and the third stimulation portion **40A** are asymmetrically arranged. The length of the second stimulation portion **30A** is different to that of the third stimulation portion **40A**.

In the present embodiment, the second stimulation portion **30A** and the third stimulation portion **40A** protrude from different positions, and the second stimulation portion **30A** and the third stimulation portion **40A** are bent, the end of the third stimulation portion **40A** away from the main body **10A** is closer to the elongated arm **20A** than a middle portion of the third stimulation portion **40A**.

Further, the third stimulation portion **40A** includes a plurality of spherical portions **41** which are sequentially connected. The sizes of the plurality of spherical portions **41** are gradually decreased the side adjacent to the main body **10A**.

In this embodiment, the main body **10A** further comprises a decorative member **102** to improve the overall appearance of the sexual stimulation device **100A**.

In this embodiment, the cover member **90A** is arranged at the out surface of the sexual stimulation device **100A**, except for the decorative member **102**, to make the outer surface of the sexual stimulation device **100A** soft and obtain a better experience.

Third Embodiment

The third embodiment of the present disclosure will be illustrated below based on FIG. 11 to FIG. 14. In addition, for the convenience of illustration, the same reference numerals are marked for components with the same function as those described in the above embodiments, and their illustrations are omitted.

In the present embodiment, the main body **10B** of the sexual stimulation device **100B** includes the first end **12B** and the second end **13B** arranged opposite to the first end

12B. The main body **10B** may be hemispherical shape which has gradually decrease size from the first end **12B** and the second end **13B**.

The elongated arm **20B** of the present embodiment may be roughly in a shape of a water droplet, and the maximum size of the first stimulation portion **22B** is greater than the size of the connecting portion **21B**.

The sexual stimulation device **100B** of the present embodiment further includes a connecting rod **61** extending from the main body **10B** to the elongated arm **20B** for supporting the elongated arm **20B**.

In the present embodiment, the second stimulation portion **30B** and the third stimulation portion **40B** are arranged on the first end **12B** of the main body **10B**, with a cross section being cone-shaped, and no motor is arranged inside the second stimulation portion **30B** and the third stimulation portion **40B**. The oscillations generated by the second stimulation portion **30B** and the third stimulation portion **40B** are caused by the driving effects of the driver portion **53B** of the driving mechanism **50B**.

In the present embodiment, the sexual stimulation device **100B** further includes an edge portion **62** of the first end **12B** of the main body **10B**. The extension direction of the edge portion **62** is the same as the extension directions of the second stimulation portion **30B** and the third stimulation portion **40B**.

In this embodiment, the edge portion **62** extends along the side wall of the first end **12B** of the main body **10B**. The first ends **12B** forms a groove **63**, the elongated arm **20B**, the second stimulation portion **30B** and the third stimulation portion **40B** extend from a bottom **64** of the groove **63**.

In the present embodiment, a protrusion height of the edge portion **62** is less than a protrusion height of the second stimulation portion **30B** and the third stimulation portion **40B**. Therefore, the edge portion **62** will not hinder the movement of the elongated arm **20B**, the second stimulation portion **30B** and the third stimulation portion **40B**. Herein, the protrusion height of the edge portion **62** refers to the length of the edge portion **62** extending from the end wall of the first end **12B** of the main body **10B**, while the protrusion heights of the second stimulation portion **30B** and the third stimulation portion **40B** refer to the length of the second stimulation portion **30B** and the third stimulation portion **40B** extending from the end wall of the first end **12B** of the main body **10B**.

The driving motor **51B**, the transmission **52B**, and the two driver portions **53B** of the driving mechanism **50B** are arranged in the first accommodating portion **11B**, and their structures have been adjusted accordingly based on the appearance of the sexual stimulation device **100B**. In addition, the cover member **90B** is wrapped around the outer circumference of the shell **80B** and the two driver portions **53B**, that is, the cover member **90B** is wrapped around the overall outer circumference of the sexual stimulation device **100B**, thereby having better sealing performance.

Fourth Embodiment

The fourth embodiment of the present disclosure will be illustrated below based on FIG. 15 to FIG. 16. In addition, for the convenience of illustration, the same reference numerals are marked for components with the same function as those described in the above embodiments, and their illustrations are omitted.

In the sexual stimulation device **100C** of the present embodiment, the elongated arm **20C** further comprises a non-linear portion **24C** arranged between the first stimula-

tion portion 22C and the connecting portion 21C of the elongated arm 20C and configured for providing necessary space for expansion and contraction movements of the elongated arm 20C.

In addition, the second stimulation portion 30C and the third stimulation portion 40C cooperatively form as an upper edge of one end of the main body 10C. The second stimulation portion 30C and the third stimulation portion 40C encircle the elongated arm 20C with most of the elongated arm 20C extending out of the second stimulation portion 30C and the third stimulation portion 40C along the length direction of the elongated arm 20C. Each of the second stimulation portion 30C and the third stimulation portion 40C comprises a cavity 33, a second motor 70C is provided in the cavity 33 to drive the second/third stimulation portion 30C/40C to vibrate. In this way, the second stimulation section 30C and the third stimulation section 40C also have a vibration function while swinging, thereby obtaining better experience.

In the present embodiment, the second stimulation portion 30C and the third stimulation portion 40C are not separated with each other. The lateral edges of the second stimulation portion 30C are seamlessly connected with lateral edges of the third stimulation portion 40C. That is, the majority of both the second stimulation portion 30C and the third stimulation portion 40C are continuous, with only a minor portion being discrete. Only one second motor 70C is arranged to drive the vibrations of the second stimulation portion 30C and the third stimulation portion 40C.

In use, both of the second stimulation portion 30C and the third stimulation portion 40C move towards the elongated arm 20C at a certain time. Afterwards, both of the second stimulation portion 30C and the third stimulation portion 40C move away from the elongated arm 20C at another certain time. The second stimulation portion 30C and the third stimulation portion 40C thus may simulate movements of human's lips.

In the present embodiment, the driving mechanism 50C further includes a driving rod 54 and a connecting rod 55. The driving rod 54 is arranged in the first accommodating portion 11C and connected with the driving motor 51C. The connecting rod 55 extends into the elongated arm 20C to support the elongated arm 20C and control the contraction and expansion of the elongated arm 20C.

Fifth Embodiment

The fifth embodiment of the present disclosure will be illustrated below based on FIG. 19. In addition, for the convenience of illustration, the same reference numerals are marked for components with the same function as those described in the above embodiments, and their illustrations are omitted.

In the present embodiment, the sexual stimulation device 100D includes a groove 63D defined at an end surface of the main body 10D. A plurality of stimulation portions 30D and the elongated arm 20D are arranged on a bottom wall 64D of the groove 63D. The plurality of stimulation portions 30D are arranged in a plurality of circles. The stimulation portions 30D between adjacent circles offset to each other.

When the sexual stimulation device 100D is in operation, at least some of the plurality of stimulation portions 30D swing towards the elongated arm 20D at a certain time, and then move away from the elongated arm 20D at another certain time, such that the plurality of stimulation portions 30D can be contracted and expanded like petals.

In other embodiments, a plurality of stimulation portions 30D are capable of auto-rotation, vibration and performing other movements.

In addition, an end of the edge portion 63D away from the main body 10D is arranged in a non-linear manner, to improve aesthetics.

Sixth Embodiment

10 The sixth embodiment of the present disclosure will be illustrated below based on FIG. 20 to FIG. 25. In addition, for the convenience of illustration, the same reference numerals are marked for components with the same function as those described in the above embodiments, and their illustrations are omitted.

In the sexual stimulation device 100E of the present embodiment, the elongated arm 20E includes a connecting portion 21E and a first stimulation portion 22E connected to the connecting portion 21E.

20 In the present embodiment, the second stimulation portion 30E and the third stimulation portion 40E are provided spaced apart from the connecting portion 21E. When the elongated arm 20E swings along a first plane, the second stimulation portion 30E and the third stimulation portion 40E swing towards and spaced apart from the elongated arm 20E along a second plane which is perpendicular to the first plane.

25 In this embodiment, each of the second stimulation portion 30E and the third stimulation portion 40E includes a driver portion 55E, and details of the driver portions 55E will be described later.

30 Referring to FIG. 21 to FIG. 23, the driving mechanism 50E includes a driving motor 51E, a fixing portion 52E, a screw 53E, and a pushing assembly 54E.

35 The driving motor 51E includes a rotating shaft 511 extended from one end of the driving motor 51E along the longitudinal direction X of the sexual stimulation device 100E. The rotating shaft 511 can rotate under the drive of the driving motor 51E. The rotating shaft 511 includes a shaft portion 5111 and a bending portion 5112. The bending portion 5112 is provided at one end of the shaft portion 5111 away from the driving motor 51E and forms an included angle α with the shaft portion 5111 (see FIG. 25). Further, the angle α between the bending portion 5112 and the shaft portion 5111 is in a range from 3 degrees to 60 degrees, so that the first stimulation portion 22E is inclined at a predetermined angle relative to the connecting portion 21E, and rotates within a corresponding angle range, thereby facilitating control of the elongated arm 20E to swing within a preferable range.

40 The fixing portion 52E is fixedly disposed at an end of the bending portion 5112 away from the shaft portion 5111, and 45 fixedly disposed in the elongated arm 20E, so as to drive the first stimulation portion 22E of the elongated arm 20E to rotate around the extending direction of the elongated arm 20E when the driving motor 51E drives the rotating shaft 511 to rotate.

50 In this embodiment, the bending portion 5112 forms the third included angle θ with the shaft portion 5111, and when 55 the driving motor 51E is started, the rotating shaft 511 rotates and drives the bending portion 5112 to rotate and swing, the stimulation portion 22E can rotate and swing following the bending portion 5112.

60 The screw 53E is fastened at an end of the shaft portion 5111 adjacent to the driving motor 51E. An outer circum-

11

ferential surface of the screw **53E** is provided with a helical groove **531**, and an abutting portion **532** is provided in the helical groove **531**.

The pushing assembly **54E** is movably arranged on the screw **53** and includes a first pusher **541** and a second pusher **542**. The first pusher **541** includes a first through hole **5411** arranged at a substantially central portion thereof and a first recess **5412** (see FIG. 4) recessed from an inner wall of the first through hole **5411**.

The second pusher **542** includes a second through hole **5421** and a second recess **5422** recessed from an inner wall of the second through hole **5421**. The first through hole **5411** is aligned with the second through hole **5421** to form a through hole for a screw to pass therethrough. The first recess **5412** and the second recess **5422** cooperate to form a groove for accommodating the abutting portion **532** (see FIG. 4).

In this way, a part of the abutting portion **532** is accommodated in the groove, and another part of the abutting portion **532** is accommodated in the helical groove **531**. Thus, when the driving motor **51** is started, the screw **53E** rotates along with the rotation of the rotating shaft **511E**, and the abutting portion **532** moves along the helical groove **531**, simultaneously driving the pushing assembly **54E** to reciprocate along a length direction of the screw **53**.

An end of each driver portion **55E** is rotatably connected to an end of the pushing assembly **54E**, and another end of each driver portion **55E** extends into the corresponding one of the second stimulation portion **30E** and the third stimulation portion **40E**.

Each driver portion **55E** includes a first driver portion **551**, an intermediate portion **552** and a second driver portion **553** which are arranged in sequence, and an obtuse angle is formed between the first driver portion **551** and the second driver portion **553**. The first driver portion **551** is rotatably connected to the pushing assembly **54E** by a connecting shaft **554**. When the pushing assembly **54E** moves towards the main body **10**, the second driver portions **553** move towards the elongated arm **20E**. When the pushing assembly **54E** moves away from the main body **10**, the second driver portions **553** move away from the elongated arm **20E** and perform reciprocating swinging motion.

Both sides of the middle portion **552** are provided with a rotating shaft **5521**, and each transmission **55E** is rotatably arranged on the shell **80** by the rotating shaft **5521**. Therefore, under the driving of the driving motor **51E**, the second stimulation portion **30E** and the third stimulation portion **40E** can swing with the corresponding driver portion **55E**, and the elongated arm **20E** can perform swinging motion with the pushing assembly **54E**.

Seventh Embodiment

Referring to FIG. 26 to FIG. 28, the first stimulation portion **22F** of the elongated arm **20F** is movable telescopically with respect to the main body **10F** in a longitudinal direction of the sexual stimulation device **100F** under the driving of the driving mechanism **50F**.

In this embodiment, the shell **80F** has a T-shaped structure. The shell **80F** includes a horizontal portion **81** and a vertical portion **82** perpendicular to the horizontal portion **81**.

Referring to FIG. 27 to FIG. 28, the driving mechanism **50F** is arranged in the vertical portion **82**, and the driving mechanism **50F** includes a driving motor **51F**, a screw **53F**, a pushing member **55F**, and an abutting member **56F**.

12

The driving motor **51F** includes a rotating shaft **511F**, and the rotating shaft **511F** extends from an end of the driving motor **51F** along the longitudinal direction **X** of the sexual stimulation device **100F** and is capable of rotating under the action of the driving motor **51F**.

In this embodiment, the driving motor **51F** is a decelerating motor.

The screw **53F** is fixedly disposed on the rotating shaft **511F** and rotates along with rotation of the rotating shaft **511F**. A spiral groove **531F** is formed in an outer peripheral surface of the screw **53F**.

The push assembly **54F** is movably disposed on the screw **53F**. Specifically, the push assembly **54F** includes a first pusher **541F** and two second pushers **542F**.

The first pusher **541F** is located at a side adjacent to the first stimulation portion **22F** and sleeved on the screw **53F**, and the first stimulation portion **22F** is sleeved on the first pusher **541F** and configured for pushing the first stimulation portion **22F** of the elongated arm **20F** to perform a telescopic movement relative to the connecting portion **21F**. The two second pushers **542F** extend from a peripheral edge of one side of the first pusher **541F** away from the first stimulation portion **22F** to the main body **10F**. The two second pushers **542F** are configured for surrounding the driving motor **51F** and rotatably connected to the corresponding driver portions **57**, respectively, so as to drive the second stimulation portion **30F** and the third stimulation portion **40F** to swing relative to the main body **10F**.

In this embodiment, the second pushers **542F** includes two pusher rods **543F**, the two pusher rods **543F** are configured to surround the driving motor **51F** and rotatably connected to the corresponding driver portion **55F**, respectively.

One end of the abutting member **56F** is fixedly arranged on the first pushing member **551F**, and the other end of the abutting member **56F** is accommodated in the spiral groove **531**. When the screw **53F** rotates along with the rotation shaft **511F** of the driving motor **51F**, the abutting member **56F** moves along the spiral groove **531**, thereby driving the pushing member **55F** to move in the extension direction of the screw **53F**, so that the movement portion **22F** can be driven to extend and retract.

In this embodiment, the elongated arm **20F** further includes a pleat portion **25**, the pleat portion **25** is arranged at the end of the elongated arm **20F** adjacent to the main body **10F** and configured for providing necessary space for expansion and contraction movements of the elongated arm **20F**.

When the swing driving device **100F** operates, the screw **53F** rotates along with the rotation of the rotating shaft **511F**, the abutting member **56F** moves along the spiral groove **531** while driving the pushing member **55F** to move along the lengthwise direction **X** of the sexual stimulation device **100F**. When the push assembly **54F** moves towards the elongated arm **20F**, the elongated arm **20F** is pushed to move in a direction away from the main body **10F**. That is, the elongated arm **20F** is in an extended state, and at this time, the second pushers **542F** are also moved towards the first stimulation portion **22F**, the driver portion **55** moves away from elongated arm **20F**. When the push assembly **54F** moves towards the main body **10F**, the elongated arm **20F** is pulled to move towards the main body **10F**, that is, the telescopic portion **20F** is retracted, and at this time, the second pushers **542F** move away from the elongated arm **20F**. When the elongated arm **20F** performs the reciprocating telescopic movement, the second stimulation portion

30F and the third stimulation portion 40F swings reciprocally, thereby realizing the meshing movement.

What is claimed is:

1. A sexual stimulation device comprising:

a main body;

an elongated arm configured to be placed in a vagina, the elongated arm connected to the main body and a first stimulation portion arranged at a distal end of the elongated arm away from the main body, the first stimulation portion configured for stimulating a first region;

a second stimulation portion arranged at a left side of the elongated arm, wherein the second stimulation portion is capable of being placed in the vagina and configured for swinging reciprocally between a first position and a second position so as to stimulate a second region, the second region being different from the first region, the first position is at a front side of the elongated arm, the second position is at a rear side of the elongated arm; and

a third stimulation portion arranged at a right side of the elongated arm, wherein the third stimulation portion is capable of being placed in the vagina and configured for swinging reciprocally between a third position and a fourth position so as to stimulate a third region, the third region being different from the first stimulation region and the second stimulating region, the third position is at the front side of the elongated arm and opposite to the first position, the fourth position is at the rear side of the elongated arm and opposite to the second position; and

a driving mechanism comprising at least one driving motor configured for driving the second stimulation portion and the third stimulation portion to swing reciprocally,

wherein the elongated arm, the second stimulation portion and the third stimulation portion are directly coupled to a same end of the main body and arranged along an arrange line which is parallel to a lateral direction of the sexual stimulation device,

wherein the second stimulation portion, the elongated arm and the third stimulation portion at least partially overlap with one other in the lateral direction of the sexual stimulation device, while at least a part of the second stimulation portion, the elongated arm and the third stimulation portion are spaced from one another at a direction which is orthogonal to the arrange line, and wherein the elongated arm is swingable in a first swing plane perpendicular to the arrange line, the second stimulation portion is configured to swing in a second swing plane which is obliquely intersected to the first swing plane, the third stimulation portion is configured to swing in a third swing plane which is obliquely intersected to the first swing plane.

2. The sexual stimulation device according to claim 1, wherein a first included angle defined by the first swing plane and the second swing plane ranges from greater than zero (0) degrees and no more than 60 degrees, a second included angle defined by the first swing plane and the third swing plane ranges from greater than zero (0) degrees and no more than 60 degrees, a third included angle defined by the second swing plane and the third swing plane ranges from greater than zero (0) degrees and no more than 90 degrees.

3. The sexual stimulation device according to claim 1, wherein the elongated arm comprises a neck portion coupled to the main body, a width of the neck portion is smaller than a width of the first stimulation portion, the neck portion

comprising two concave portions at on opposite sides of the neck portion, and the second stimulation portion and the third stimulation portion are disposed beside the two concave portions.

5. The sexual stimulation device according to claim 3, wherein the sexual stimulation device is switchable between an original state and a pressed state, wherein in the pressed state, the second stimulation portion and the third stimulation portion are pressed towards corresponding concave portions of the two concave portions.

6. The sexual stimulation device according to claim 4, wherein in the original state, a maximum lateral width from the second stimulation portion to the third stimulation portion is larger than the width of the first stimulation portion, and in the pressed state, the maximum lateral width from the second stimulation portion to the third stimulation portion is substantially equal to the width of the first stimulation portion.

7. The sexual stimulation device according to claim 1, 20 wherein the sexual stimulation device further comprises a control circuit arranged in the main body, the control circuit is configured to cause the sexual stimulation device to be in a first control mode or in a second control mode, wherein:

in the first control mode, the second stimulation portion and the third stimulation portion swing at a same frequency in a same swing direction for a preset time period; and

in the second control mode, the second stimulation portion and the third stimulation portion swing at a same frequency in opposite swing directions for a preset time period.

8. The sexual stimulation device according to claim 1, 35 wherein each of the second stimulation portion and the third stimulation portion comprises a connecting end connecting with the main body and a distal end away from the main body, the distal end is rotatable around a central axis of the second stimulation portion or the third stimulation portion.

9. The sexual stimulation device according to claim 1, 40 wherein each of the second stimulation portion and the third stimulation portion comprises a connecting end connecting with the main body and a distal end further away from the main body than the connecting end, at least one corresponding distal end of the second stimulation portion and the third stimulation portion comprises a vibration motor, the vibration motor is configured to drive the corresponding distal end to vibrate.

10. The sexual stimulation device according to claim 1, 50 wherein the driving mechanism further comprises a transmission configured for changing rotation speeds of the driving motor, and two driver portions arranged inside the main body,

the at least one driving motor is connected to the transmission,

the two driver portions are configured to drive a corresponding stimulation portion of the second, and the third stimulation portions such that the second, and the third stimulation portions are driven to swing by the at least one driving motor, one end of each of the two driver portions engages with the transmission, and another end of each of the two driver portions engages with the corresponding stimulation portion.

11. The sexual stimulation device according to claim 9, 65 wherein each of the second stimulation portion and the third stimulation portion comprises a cover member having a hardness less than a portion of the driving mechanism which is connected to the second stimulation portion and the third stimulation portion.

11. The sexual stimulation device according to claim 1,
wherein the first stimulation portion of the elongated arm is
movable telescopically with respect to the main body in a
longitudinal direction of the sexual stimulation device.
